UNITED STATES PATENT OFFICE.

FOSTER C. PHELPS, OF WAUKESHA, WISCONSIN.

HUMIDIFIER.

1,158,553.

Specification of Letters Patent. Patented Nov. 2, 1915.

Application filed August 25, 1913. Serial No. 786,411.

To all whom it may concern:

Be it known that I, FOSTER C. PHELPS, a citizen of the United States, and resident of Waukesha, in the county of Waukesha and State of Wisconsin, have invented new and useful Improvements in Humidifiers, of which the following is a description, reference being had to the accompanying drawings, which are a part of this specification.

10 This invention relates to improvements in humidifiers and more particularly to humidifiers for household and other use.

It is one of the objects of the present invention to provide a humidifier for increasing the humidity of air by evaporating water from a container at a greater rate than would be evaporated under ordinary circumstances and, therefore, conduce to the comfort and health of the occupants of the 20 rooms.

A further object of the invention is to provide a means for increasing the humidity of the air by suspending a number of sheets of absorbent material in such position as to receive a constant supply of water by capillary attraction and to subject the moistened sheets to the circulation of the air in the room.

30 A further object of the present invention is to provide a humidifier for increasing the humidity of the air which is automatic in action and which may be placed adjacent to heating radiators of different kinds.

A further object of the invention is to 35 provide a humidifier for increasing the humidity of the air formed of a number of units which may be increased or diminished in number to regulate the degree of humidity desired.

40 A further object of the invention is to provide a humidifier for increasing the humidity of the air which is of simple construction, is strong and durable and is well adapted for the purpose desired.

45 With the above, and other objects in view, the invention consists of the improved humidifier and its parts and combinations as set forth in the claim, and all equivalents thereof.

50 In the accompanying drawings in which the same reference characters indicate the same parts in all of the views: Figure 1 is a side view of the improved humidifier, the

container and some of the absorbent sheets being shown in section; Fig. 2 is a vertical 55 sectional view thereof taken on lines 2—2 of Fig. 1; Fig. 3 is a vertical longitudinal sectional view of a modified form of the humidifier; Fig. 4 is a vertical transverse sectional view thereof; Fig. 5 is a side view 60 of a steam or hot water radiator having a modified form of humidifier mounted therein; Fig. 6 is a vertical transverse sectional view thereof.

Referring to the drawings the numeral 15 indicates a receptacle of rectangular form 65 for holding water to be evaporated and within this receptacle is placed a rectangular wire frame 16 which projects upwardly 70 above the said receptacle from the opposite end portions thereof. A number of absorbent units in the form of sheets of absorbent material 17 preferably of blotting paper, are mounted on a horizontal member 18 and the 75 said member in turn rests upon the wire frame 16. The sheets are of T-form and have their stem portions 19 extending into the receptacle and their upper portions 20 projecting above and beyond the side walls 80 of the receptacle. The upper medial portions of the absorbent units are provided with openings 21 through which the horizontal member extends and the said horizontal member is provided with transverse notches 22 on its upper edge to receive and 85 space the absorbent units apart.

In the use of the form just described, the receptacle is filled with water and the lower portions of the absorbent units are placed 90 therein and by capillary attraction will draw the water from the receptacle until all portions of the units are saturated thus exposing comparatively a large moist surface to the air circulating between the units.

In the modified form shown in Figs. 3 95 and 4 the absorbent units 23 are formed in pairs reinforced and supported by sheets of interposed wire netting 24, the three parts being held together by spring paper fasteners 25. In this form the pairs of units are 100 spaced apart by providing the rectangular frame 26 with upper and lower corrugations 27 into which the units extend.

In the modified form shown in Figs. 5 105 and 6 the reinforced absorbent units 28 are supported on a frame in the form of a pair

of notched horizontal members 29 which extend through openings 30 in the units and are connected to the radiator by hooks 31 or in any other manner desired. These horizontal members also provide for elevating the units to permit the removal of the receptacle for filling or for other purposes. This form is particularly adapted for use in connection with steam or hot water radiators as indicated by the numeral 32. When thus used the receptacle 15' is slipped under the radiator and the absorbent units are then placed between the coils of the radiator and into the receptacle. In order to permit the units to be thus positioned they are slotted as indicated by the numeral 33 to permit them to straddle the connecting pipe 34 of the radiator.

All of the modified forms are used in substantially the same manner before described.

From the foregoing description it will be seen that the humidifier is arranged to expose comparatively a large area of moist surfaces to the air and that a considerable amount of moisture may be evaporated. It will also be seen that by varying the number

of units the degree of moisture may be regulated.

What I claim as my invention is:

A humidifier, comprising a receptacle 30 having an open top, a removable rectangular wire frame mounted in said receptacle and provided with means extending horizontally and longitudinally across its top and having notches formed therein, and a plurality of absorbent units supported by said frame, bodily removable therewith, and directly engaging in said notches to retain them in spaced relation with their lower ends projecting into said receptacle to contact with the water contained therein, said horizontal notched means being adapted to be positioned longitudinally between the coils of a radiator to support said absorbent units transversely between the coils of the same.

In testimony whereof, I affix my signature, in presence of two witnesses.

FOSTER C. PHELPS.
